UNITED STATES PATENT OFFICE.

WILLIAM H. HAWKEN, OF HONESDALE, PENNSYLVANIA, ASSIGNOR TO IRVING CUT
GLASS COMPANY, INC., OF HONESDALE, PENNSYLVANIA.

DESIGN FOR A BOWL OR SIMILAR ARTICLE.

Application filed April 6, 1922. Serial No. 1,566. Term of patent 3½ years.

To all whom it may concern:

Be it known that I, WILLIAM H. HAWKEN, a citizen of the United States, residing at Honesdale, in the county of Wayne and State of Pennsylvania, have invented a new, original, and ornamental Design for a Bowl or Similar Article, of which the following is a specification, reference being had to the accompanying drawing, forming part thereof.

Fig. 1 is a bottom plan view of a bowl, showing by new design.

Fig. 2 is a side elevation thereof on a reduced scale, the ornamentation shown in Fig. 1 being omitted.

I claim:

The ornamental design for a bowl or similar article, as shown.

WILLIAM H. HAWKEN.
